US00D789922S

(12) **United States Design Patent** (10) **Patent No.:** **US D789,922 S**
(45) **Date of Patent:** ** *Jun. 20, 2017

(54) **PORTABLE INFORMATION TERMINAL**

(71) Applicant: **SEMICONDUCTOR ENERGY
LABORATORY CO., LTD.,**
Atsugi-shi, Kanagawa-ken (JP)

(72) Inventors: **Shunpei Yamazaki**, Tokyo (JP);
Kensuke Yoshizumi, Kanagawa (JP)

(73) Assignee: **Semiconductor Energy Laboratory
Co., LTD.**, Kanagawa-ken (JP)

(*) Notice: This patent is subject to a terminal disclaimer.

(**) Term: **14 Years**

(21) Appl. No.: **29/497,465**

(22) Filed: **Jul. 24, 2014**

(30) **Foreign Application Priority Data**

Jan. 31, 2014 (JP) 2014-001996

(57) **CLAIM**

We claim, the ornamental design for a portable information terminal, as shown and described.

DESCRIPTION

FIG. 1 is a front view of a portable information terminal showing our new design;

FIG. 2 is a rear view;

FIG. 3 is a right side view;

FIG. 4 is a left side view;

FIG. 5 is a top view;

FIG. 6 is a bottom view;

FIG. 7 is a front perspective view;

FIG. 8 is a rear perspective view;

FIG. 9 is a front perspective view in which a flexible display is unfolded;

FIG. 10 is a rear perspective view in which the flexible display is unfolded; and,

FIG. 11 is an enlarged sectional view taken from A-A' in

FIG. 1 with the internal mechanisms omitted.

The portable information terminal is used in a state in which the flexible display is folded, unfolded or curved as necessary.

1 Claim, 6 Drawing Sheets
